US00D566148S

(12) **United States Design Patent** (10) **Patent No.:** **US D566,148 S**
Akita (45) **Date of Patent:** **** Apr. 8, 2008**

(54) **VIDEO CAMERA**

(75) Inventor: **Miho Akita**, Tokyo (JP)

(73) Assignee: **Sony Corporation**, Tokyo (JP)

(**) Term: **14 Years**

(21) Appl. No.: **29/263,138**

(22) Filed: **Jul. 18, 2006**

(30) **Foreign Application Priority Data**

Mar. 16, 2006 (JP) D2006-006621

(51) **LOC (8) Cl.** **16-01**

(52) **U.S. Cl.** **D16/202**

(58) **Field of Classification Search** D16/200-205,

D16/208-209, 211-213, 218; D14/317;

348/373-376; 358/906, 909.1; 396/535-541

See application file for complete search history.
